UNITED STATES PATENT OFFICE

JOHN W. SMITH, OF PHILADELPHIA, PENNSYLVANIA

MEANS FOR ROLLING DISK WHEELS

Application filed May 15, 1924. Serial No. 718,425.

This invention relates to a novel manner of rolling disk wheels for vehicles such as automobiles and the like, and also to means useful to this end.

5 The primary object of my invention is to produce from a roughly prepared blank, an extremely light and strong disk wheel characterized by an integral hub, a dished cross section for sturdiness against lateral thrust, 10 and radial tapering of the metal to a degree of fineness hitherto impossible of attainment.

Attempts have been made to produce a disk wheel having the attributes outlined by drop-hammer forging, or the use of hydraulic 15 presses and bulldozers, but it has proved absolutely impossible to obtain a cross section of suitable thinness to meet the critical requirements associated with a light wheel for automobile use, on account of the inherent 20 molecular resistance of metal to flow in a direction at right angles to that of applied force. To overcome the disadvantage referred to, and according to my invention, I employ narrow faced rollers mounted with 25 capacity for cycloidal oscillation by a novel form of mechanism.

Subsidiary objects and advantages, will be apparent from the following description of a typical embodiment of my invention, the appended claims serving to indicate the features 30 which I believe to be novel and patentable.

In the drawings, Fig. I is a side elevation, showing a mill adapted for the rolling of disk wheels in accordance with this invention, 35 certain portions being, however, broken away to disclose underlying features.

Fig. II is a longitudinal section of the greater portion of the mill on a somewhat enlarged scale.

40 Fig. III is a transverse vertical view taken as indicated by the arrows III—III in Figs. I and II.

Fig. IV is a diagrammatic sectional view taken approximately on a plane as indicated by the arrows IV—IV in Fig. I, to show a controlling mechanism for the mill rollers, 45 as well as means for intermittently progressing a turret whereby the blanks are successively presented for rolling.

50 Fig. V is a transverse sectional view taken

as indicated by the arrows V—V in Fig. I, showing the mechanism for moving the mill rollers toward and away from the forming die.

Fig. VI is a sectional view showing a means 55 whereby the roller axes may be adjusted to compensate for wear; and

Figs. VII and VIII are diagrammatic illustrations showing successive steps in the rolling operation.

60 Referring to said drawings, I will firstly describe the operation of the main instrumentalities by which the disk forming is directly accomplished. To this end reference is had to Figs. VII and VIII wherein the 65 numeral 1 indicates the forming die, and 2, cooperating rollers whereof there may be several, two being, however, deemed ordinarily sufficient. The face of the die 1 is given, what I preferably term, an "arcographic" cross 70 sectional profile that determines the general configuration of the finished article. Use of the term "arcographic", hereinafter, is intended to broadly apply to a sectional profile of a curvature not struck from a common center but rather of gradual deviation therefrom.

75 In the manufacture of disk wheels for vehicles, the die-face is formed with a cycloidal concavity 3 that is symmetrical relative to the vertical axis about which the die 1 is rotated. The rough blank wherefrom the disk wheel is fashioned and shown at "B" in Fig.

80 VII, may be produced by drop forging from an ingot of predetermined size and bulk, with a circular disk portion and an integral frusto-conical axial boss H, which is ultimately to become the wheel hub. The discous portion of the blank B—shown as an example only—

85 tapers in cross section at the region of its emergence a with the hub boss H, and also at the region of its periphery b. The bore of the boss H is coned inwardly from the opposite ends c, d to facilitate support on the one hand by a stud 4, which, together with

90 others is mounted on a feeding means to be hereinafter described, and on the other hand, by a centering pin 5 located medially of the die 1. When the blank B is properly positioned, the tapered hub-boss H is accommodated with a firm and snug fit in a corre- 95 100

spondingly-tapered portion 6 of the die-bore under upward pressure maintained on the stud as hereinafter noted, to prevent relative movement between the blank B and the die 1 during rolling. Upon placement of the blank B as just explained, the rollers 2 are simultaneously elevated under pressure exerted from beneath, from the full-line to the dotted-line position in Fig. VII, with the result the 10 discous yields to upward bending during the first pass of the rollers 2. After a slight pause in the initial attack the rollers 2 are moved outward and at the same time swung bodily upon centers determining a curvilinear course 15 substantially in parallelism to the cycloidal concavity 3 on the die face. As a consequence, the metal of the blank B is urged forward by the rollers 2, determining radial flow which is attended both by radial and compensative 20 circumferential expansion of said blank, brought about by the narrow faced rollers 2 rotating upon the metal in a cycloidal direction. To attain this end, the rollers 2 are mounted in trunnions with capacity for adjusting their movement of deviation relative 25 to the center of the cycloidal concavity 3, and thereby control the ratio of metal thickness at the hub zone and outer periphery of the disk.

30 By proper determination of the axis about which the rollers 2 are oscillated, I am enabled to obtain an attenuated cross section that is highly desirable in disk wheels for automobiles. Thus by respectively swinging 35 the rollers 2 bodily on a center slightly eccentric to that of the die curvature, I obtain the outwardly attenuated cross sectional configuration of blank shown in dotted lines in Fig. VII, and in full lines in Fig. VIII. A 40 greater degree of thinness with corresponding radial and circumferential expansion of the blank B may be had by a second pass of the rollers 2, but with said rollers operating progressively closer to the die 1. The result 45 of a second pass, carried out as suggested, is shown in dotted lines in Fig. VIII, the difference being made apparent by contrast with the full line cross section obtained by the initial rolling. In practice I have found that 50 the operation of rolling in accordance with my invention may be accomplished with the utmost ease when the blank is preheated, the metal flowing without any tendency whatever 55 to buckle or fracture. Furthermore, by using rollers 2 with comparatively narrow spherical treads 7, as herein shown, the first pass may be completed without any appreciable temperature drop in the blank B, so that the second pass can be accomplished under the same 60 favorable conditions without necessity for reheating the blank. With the mill now to be described it is possible to completely roll a wheel by two passes in approximately eighteen seconds, and even in less time.

65 Referring generally to Figs. I to V of the drawings, it will be seen that the forging die 1 is rotatably held in suspension by a hollow head 10, supported by tubular columns 11 above a base 12. This head 10 is rectangular in plan and formed with integral 70 projecting corner bosses 13 bored to fit the upper reduced ends of the columns 11, as shown in section in Fig. I. To permit slight vertical adjustment of the head 10, I provide, collars 14 that engage threaded portions 15 of the columns 11; companion collars 16 in similar engagement with the upper ends of rods 17 extending axially through said columns 11, serving to fix the position of the head 10 after the desired adjustment is made. 75 As shown to best advantage in Fig. II, the die 1 is bolted to the lower circumferentially extended portion 18 of a swivel member 19 journaled centrally in the head 10 with anti-friction roller bearings 80 20 that take its axial thrust. The swivel member 19 is maintained in the assemblage by a cap piece 21 sustained upon a horizontal annular ledge 22 formed in the base of a central top cavity 23 of said head. The upward pressure imparted to the die 1 during the rolling operation is resisted by a thrust bearing 24 which is designed to insure absolute freedom of motion and amply proportioned 85 to withstand the heavy strains that it is subjected to. The bearing 24 is accommodated within a lower hollow 25 of the head 10, set apart by a horizontal diaphragm 26. The circumferential portion 18 of the swivel member 19 has an integral upstanding peripheral flange 27 that extends into the lower cavity 25 and provides an oil well for immersion of the thrust bearing 24, the top edge of said flange being turned outwardly and 90 downwardly to overlap an annular vertical flange 28 of a cover plate 29 closing the cavity 25. As a means for driving the swivel member 19 I may employ any convenient type of prime mover, for example an electric motor represented conventionally by the dotted lines 30 in Fig. II, and shown as supported upon the top of the head 10 across its upper center cavity 23. The shaft of the motor 30 carries a clutch collar 31 designed to engage 95 directly with the cap piece 21 crowning the swivel member 19, said cap piece being formed with vertically projecting lugs 32 for this purpose.

100 The centering pin 5, previously referred to, is secured to the lower end of a plunger 33 independently rotatable and free to reciprocate in a guide housing 34 accommodated —with circumferential clearance—in the hollow of the swivel member 19. A helical spring 35 surrounding the reduced portion of the plunger 33 and engaging the shoulder afforded by its broader bottom end, serves to urge the pin 5 downward or outward through the die 1, the limit of such motion being determined by a stop plate 36 that slightly over- 105

110

115

120

125

130

laps the open end of the guide housing 34 and intercepts a circumferential protuberance 37 of the plunger 33.

In order to insure proper lubrication of the various bearings associated with the head 10, and at the same time to dissipate the heat transmitted to them by conduction from the die 1, I maintain a constant circulation of a suitable lubricating medium through the head. The lubricant enters the head 10 by way of a pipe 38 that leads directly to an internal groove 39 surrounding the swivel member 19 immediately above the roller bearing 20. A portion of this supply passes through openings 40 in the head structure, said openings leading to the bearing surface 22 for the cap piece 21. In passing through the bearing just described, the oil enters the central upper cavity 23 of the head 10 and accumulates to the level shown, determined by the height of the over-flow outlet 42 which leads downwardly and discharges into the well 27 formed about the thrust bearing 24 as previously described, to lubricate said bearing. A portion of the lubricant also passes from the internal groove 39, through radial ports 43 of the swivel member 19, and enters the clearance space about the housing 34 for the centering pin plunger 33. After cooling the parts in this vicinity, the lubricant continues its course through ports 44 in the lower portion of the swivel member 19 finding its way into an annular chamber 45 about said member to assist in the lubrication and cooling of the thrust bearing 24. The overflow from the well 27 about the thrust bearing 24 discharges into the lower cavity 25 of the head 10 wherefrom it is conducted through a return pipe 46. A conventional cooling device—not shown—may be connected in the circuit of the pipes 38—46.

As will be observed from Fig. II, the rollers 2 have shafts 50, here shown integral—but they may be detachable—that are mounted in individual trunnion housings 51. Each housing 51 is formed with an integral yoke 52 from the ends of which project outwardly in respectively opposite directions, polygonal lugs 53 that provide, in conjunction with separable collars 54 thereon, the trunnions about which the housing swings to effect radial movement of the corresponding roller 2 relative to the die 1 for determining the desired cycloidal movement of the roller tread 7. The trunnions for each of the roller housings 51 are received in bearings 55 of a trunnion support 56 provided with slid able guides 57 mounted upon the columns 11 in moving the rollers 2 vertically toward and away from the die 1. By reference to Fig. III of the drawings, it will be seen that the shifting of the trunnion support 56 is controlled by aid of toggle links 58 of which there are four sets to insure absolute accuracy of the trunnion support movements. One link of each pair is

pivoted directly to the trunnion support 56, while the other is connected to the base 12, the common pivotal centers 59 of each transversely aligned pair of the toggles being joined by a link 60 for the purpose of simultaneous operation. The lower links of the pair of toggles at the left hand side of the mill, as considered in Figs. III and V, are coupled by connecting bars 61 with rocker arms 62 that are secured to a shaft 63 extending longitudinally of said mill, (see Fig. I) and journaled in bearing brackets 64, 65 rising from the base 12. The rock shaft 63 receives motion, through the instrumentality of a second arm 66 secured thereto at its left hand end (Fig. I), said arm carrying a roller 67 which rides against the edge of a rotary cam 68 fixed upon the main shaft 69, from which the various mechanisms of the mill derive their motion. As shown in Fig. V, the rotary cam 68 comprises two segmental rises 70, 71 which differ in radial depth so as to determine, during rotation of said cam in the direction of the arrow thereon, the proper successive positions of the rollers 2 relative to the die 1, as required for the two passes of the complete operation, the position of the toggles 58 for the first pass being indicated by dot-and-dash center lines in the referred to illustration. As a means for tripping the toggles 58 for the trunnion support 56, an associate cam 72 is secured to the main drive shaft 69 adjacent the rotary cam 68, said associate cam having trip projections 73, 74 that successively engage a roller arm 75 fixed to the shaft 63 with the arms 62, 66, previously referred to. Thus, after the completion of each pass, the rocker shaft 63 is actuated to upset the toggle setting to permit lowering of the trunnion support 56 and return of the rollers 2 to their normal lowered position, retracted from the die 1.

Referring again to Fig. II, it will be noticed that a roller bearing 76 is in each instance provided to take the main strain adjacent the roller 2, while an additional ball bearing 77 sustains the shaft 50 at the opposite extremity. The trunnion housings 51 are closed in at their outer ends by covers 78, bolts 79 being employed to urge the annular flange 80 against the outer ring of the ball bearings 77, and retain the same in place. The trunnion roller housings 51, as well as the bearings 76, 77 for the roller shaft 50, are cooled and lubricated by oil introduced in each instance through a pipe 81 that enters the polygonal lug 53 at the side of the mill shown in Figs. I and II. Each pipe 81 communicates with a duct 82 which spans the yoke portion of the housing 51 to supply lubricant to both sides thereof, the duct 82 being, however, interrupted by a cavity 83 which accommodates the shaft 50 of the roller 2. From this cavity 83, the oil is free to flow to both the main bearings 76, 77, as well as through the latter 130

bearings to the chamber within the cover member 78. After having performed the function of lubricating the bearings 76, 77, the oil passes through ports in a plate 84 that covers an axial passage 85 through the shaft 50, and in order to effectively cool the latter, is obliged to traverse the full length of the same before escaping, through ports 86 of a plug 87 at the roller end of said shaft, into a tube 88 which extends through the axial passage 85. This tube 88 leads to the rear end of the trunnion housing 51 from which the oil is drawn through a pipe 89 fitted into the cover member 78. The pipe 89 just referred to, is made of flexible material so as to enable swinging of the trunnion housing 51 during the rolling operation, and any appropriate means may be employed to induce circulation of the lubricant through the devious passages in said housing.

Slight adjustment of the rollers 2, may be had by the means best shown in Figs. II, III and VI, where it will be noted that the polygonal lug or trunnion 53, fits a correspondingly shaped, though wider, opening 90 in the sleeve 54. Replaceable interchangeable shims 91 are inserted between the polygonal lug 53 and one side of the opening 90, as shown, and set screws 92 taking into the sleeve 54, press said lugs or trunnions firmly against the shims 91 to hold the several parts in rigid assemblage. Wear of the roller treads 7 may be compensated for, from time to time, by interchanging the shims 91, as will be readily apparent. A further adjustment is afforded the rollers 2 by the use of a bearing lining 93 with an eccentric bore 94 to take the separable collar 54. From the lining 93 projects radially at the exterior of the bearing 55, a lug 95 having associated therewith a bolt 96 which may be engaged within any one of a number of openings 97 in the face of the bearing 55, to secure said lining in adjusted positions. This adjustment permits correction of the center of oscillation of the trunnion housing 51, with corresponding change in the relation of the tread of the roller 2 to the cycloidal concavity 3 in the die 1 and alteration of the thickness to which the blank is rolled. Still another adjustment for each of the rollers 2,—in an axial direction—may be had by the use of interchangeable shims 98 between the ball bearing 77, and the annular seat 99 therefor, at the interior of the trunnion housing 51.

The mechanism for oscillating the housings 51 about their trunnion axes, includes a rotary master cam 100, see Figs. I and IV, affixed to the main drive shaft 69 at the right of the rotary cam 68 aforementioned. This master cam 100 has two rises 101, 102 which, function successively during the two passes of the rollers 2 in rolling the blank B. The cam rises 101, 102 of the master cam 100, affect a roller arm 103 on a hollow rocker

shaft 104, located above, and extending in parallelism to the rocker shaft 63 previously described. The shaft 104 is journaled in bearings 105, 106 and adjacent these bearings has depending arms 107, 108 connected by links 109 with motion translating members 110, pivoted upon the opposite ends of an axle shaft 111, extending longitudinally through the trunnion support 56. The translating arms 110 are pitched angularly as illustrated in Figs. I and II, and are in turn coupled by links 112 respectively, with studs 113 projecting laterally from the trunnion housings 51 for the rollers 2, universal fittings 114 being employed in attachment of the links 112 to permit the freedom required for their complex movement. Thus, as the master cam 100 is rotated in the direction of the arrow in Fig. IV, it will be apparent that the trunnion housings 51 will be oscillated on the bearings 55 in 70 75 80 85 90 95 100 105 10400

with capacity for adjustment, to an arm 132 fast upon the rock shaft 104 intermediate the arms 107, 108 so as to be operable under the influence of the master cam 100 and its associated follower cam 115. During each 5 rotation of these cams 100, 115, the link 131 carrying the pawling pin 130 is reciprocated twice, but owing to the configuration of the follower cam 115 at the region 115^a, only one 10 of these movements is sufficient to effect complete retraction of the pin 130 to engage in a succeeding notch 129 so that the annulus 127 is shifted but once for each cycle of operation. The result of the shifting of the 15 annulus 127 is to bring a fresh blank B into position beneath the die 1, while the previously finished wheel disk is simultaneously conducted to a chute 134 shown in Fig. III for discharge from the apparatus, the chute 20 134 automatically stripping said previously finished disk from the supporting stud 4 during movement of the turret annulus 127. It is, of course to be understood that the shifting of the annulus 127 occurs when the trunnion 25 support 56 is in its lowered position; and that while said support is being raised, to position the blank relative to the die 1 for rolling, the saddle member 120 yields under the cushioning action of the spring 123. When the trunnion support 56 is fully elevated the spring 30 123 functions to maintain the blank B firmly pressed against the die 1, and holds it securely against displacement during rolling.

To render the studs 4 free for rotation in 35 synchronism with movement of the die 1, they are mounted in replaceable bearing sleeves 135 screwed into cavities 136 in the periphery of the annulus 127, shoulders 137 at the inner ends of said studs insuring their retention. In each instance a ball bearing 138 is also utilized to take the vertical thrust of the stud 4.

Any suitable means may be employed for imparting rotary motion to the main shaft 69; 45 for example a worm gear couple may be conveniently used, the same being concealed in the present instance within a protective casing shown at 140 in Figure I of the drawings, with a horizontal shaft 141 extending through 50 said casing for power application.

The operation of the mill is as follows:—

The blanks B are successively placed by the operative upon the studs 4 at the right hand side of the mill as considered in Figure 55 III. When the trunnion support 56 is in its lowered position, the turret annulus 127 is shifted to advance the blank B beneath the die 1 in axial alignment therewith, actuation of said annulus being effected by movement 60 of the master and follower cams 100, 115 through the various interposed connections coupled with them. As the trunnion support 56 is elevated by movement of the toggles 58 to the dot-and-dash or first pass position of 65 Fig. V, through action of the rise 70 of ro-

tary cam 68 on the main shaft 69, the blank B is brought into direct contact with the cycloidal concavity 3 in the die 1 by raising of the saddle member 120 upon which the turret annulus 127 is mounted. The approach 70 of the blank B to the die 1 is facilitated by engagement of the centering pin 5 within the tapered bore of the hub boss H, said pin 5 incidentally receding automatically with the spring 35, to which it is subject. When once 75 properly positioned, the blank B is maintained in firm contact with the die 1 during the rolling operation by compressive action of the spring 123 which urges the saddle member 120 upwardly. Concurrently with the 80 elevation of the trunnion support 56, the rollers 2 are brought into contact with the blank B in readiness to roll the same, whereupon they are simultaneously swung outwardly in a direction radially of the die 1 by 85 oscillation of their trunnion housings 51, which operation is brought about through the action of the first pass rise 101 of the master cam 100, upon the roller arm 103 and associated parts. Immediately upon 90 completion of the outward sweep of the rollers 2, the support 56 is lowered, and the arm 103 incidentally permitted to return to the 95 position shown in Fig. IV to restore said rollers 2 to the normal position shown in full lines throughout the drawings. In like manner the second pass of the rollers 2 is effected through a second upward movement of the trunnion support 56 and oscillation of the 100 housings 51 in the order mentioned. Upon completion of the two passes, whereby the blank is completely rolled in accordance with my invention, and the final lowering of the trunnion support 56, the turret annulus 127 is again shifted to present a new blank B to the die 1, and at the same time to automatically discharge the blank previously rolled on to the chute 134, for removal from the mill.

While I have shown and described my invention in connection with the manufacture 105 of automobile wheels, it is obvious that the same may be employed for production of other articles in which a dished sectional profile and tapering of the metal are required. It is also to be understood that while it is advantageous in rolling wheels in accordance 110 with my invention to effect the operation by two (or more) passes of the rollers 2, there are instances where the operation can be accomplished by a single pass as in rolling 115 heavier wheels not requiring such a high degree of attenuation. It is also pointed out that a mill such as herein described may also be employed to advantage in smoothing, shaping, and finishing a wheel otherwise fully 120 formed.

Having thus described my invention, I claim:—

1. A rolling mill comprising an arcographic die, a cooperating rolling means, and means 130

prescribing movement of the rolling means to fashion a metallic blank of attenuated cross section by outward expansion.

2. A rolling mill comprising an arcographic die, a cooperating rolling means, and means prescribing movement of the rolling means to fashion a metallic blank by outward expansion into conformity with the die, and concurrently define linear expansion of the blank to an outwardly tapering cross section.

10 3. A rolling mill comprising an arcographic die, cooperating rolling means, and means prescribing curvilinear movement of the rolling means to reduce a metallic blank by outward expansion into conformity with the die and concurrently effect diametric expansion of the blank to define an outwardly tapered cross section therefor.

20 4. A rolling mill comprising an arcographic die, a cooperating roller capable of cycloidal movement to fashion a metallic blank by outward expansion into conformity with the die and concurrently effect formation of said blank to tapered cross section, and means whereby the path of the roller movement is altered to vary the degree of taper.

30 5. A rolling mill comprising an arcographic die, and a cooperating roller capable of curvilinear movement about a point eccentric to the center of the die curvature in fashioning a metallic blank by outward expansion to conform thereto and simultaneously effect formation of the blank to outwardly tapered cross section.

35 6. A rolling mill comprising an arcographic die, a cooperating roller capable of curvilinear movement about a point eccentric to the center of the die in fashioning a flat metallic blank to conform thereto and concurrently effect expansion of said blank to tapered cross section, and means whereby the eccentric movement is varied to alter the cross-sectional taper.

45 7. A rolling mill comprising an arcographic die, and a cooperating roller capable of eccentric curvilinear movement relative thereto in effecting outward expansion of a metallic blank, said roller having a comparatively narrow tread for minimum surface contact to permit successive rollings without requiring reheating of the blank.

50 8. A rolling mill comprising an arcographic die, a cooperating roller, means for curvilinearly guiding the roller in a gradually advancing direction radially outward from the center of the die, and means for withdrawing the roller at the end of its outward pass and restoring the same to position for effecting successive passes.

60 9. A rolling mill comprising an arcographic die, a cooperating roller, means for cycloidally guiding the roller to follow substantially the configuration of the die with a graduated approach, means to determine successive passes of the roller, and means concur-

rently operative to shift the roller into closer proximity to the die face for each consecutive pass.

10 10. A rolling mill comprising an arcographic die, a cooperating roller effective to outwardly expand material rolled, a mounting whereon the roller is bodily swung to eccentrically follow the die curvature, and means for oscillating said roller outwards on the mounting during the rolling operation.

15 11. A rolling mill comprising an arcographic die, a cooperating roller, a mounting whereon the roller is bodily swung to follow the die curvature, means for oscillating the roller including a rotary cam, and motion transmitting means interposed between the cam and the roller mounting.

20 12. A rolling mill comprising an arcographic die, a cooperating roller, a mounting whereon the roller is bodily swung to follow the die curvature, means for oscillating the roller for consecutive passes including a rotary cam with a succession of radial rises, and interposed means for imparting the motion of said cam to the roller mounting.

25 13. A rolling mill comprising an arcographic die, a cooperating roller, a mounting whereon the roller is bodily swung to follow the die curvature, a rotary master cam for oscillating the roller and actuating the rocker arm, a follower cam associated with the master cam influential upon a second rocker arm to maintain the same at all times in operative contact with said master cam, and interposed means whereby the movement of said rocker arms is imparted to the roller mounting.

30 14. A rolling mill comprising an arcographic die, a cooperating roller, an elongated journal housing for the shaft of said roller, a trunnion mounting for the journal housing whereon the roller is bodily oscillated to follow the die curvature, and means determining circulation of lubricant through the trunnion mounting and back and forth in the roller journal housing to lubricate and cool the various bearings associated therewith.

35 15. A rolling mill comprising an arcographically concaved die, a cooperating roller effective to outwardly expand a blank being rolled, a mounting whereon the roller is oscillated to follow the die curvature in fashioning said blank to conform to the die, and means for shifting the mounting to move said roller toward and away from the die.

40 16. A rolling mill comprising an arcographically concaved die, a cooperating roller, a mounting whereon the roller is oscillated to differentially follow the die curvature outwards in fashioning a blank to taper cross section, and toggle links operative upon the mounting to maintain the roller in pressure contact with the blank.

45 17. A rolling mill comprising an arcographically concaved die, a cooperating roller, a mounting whereon the roller is os-

cillated to follow the die curvature, toggle links operative upon the mounting to maintain the roller in pressure relation with the die, and means controlling the toggles to successively position the mounting closer to the die concurrently with successive passes of the roller.

18. A rolling mill comprising an arco-graphically concaved die, a support for the blank to be formed movable toward and away from the die, and means operative upon the support whereby the blank is maintained yieldingly in contact with the die.

19. A rolling mill comprising an arco-graphic die, a support for the blank to be rolled, a carriage for the support movable toward and away from the die, and a spring means interposed between the support and its carriage to maintain the blank in pressure contact with the die.

20. A rolling mill comprising a die, a turret for moving blanks to be rolled successively into position relative to the die, a carriage support for the turret, means for shifting the carriage to advance the blanks into engagement with the die upon successive presentation, and means for intermittently rotating the turret when the carriage is in retracted position.

30 21. A rolling mill comprising a rotating die, a turret feed carrying a succession of freely revolvable studs for individual mounting of centrally apertured blanks to be rolled, a carriage support for the turret, means for shifting the carriage to advance the blanks into engagement with the die, and means for intermittently rotating the turret when the carriage is retracted to advance the blanks successively into aligned position relative to the die.

40 22. A rolling mill comprising a die, a support from which the die is suspended for free rotation, a roller cooperating with the face of the die, means for exerting upward pressure to urge the roller toward the die in fashioning a heated blank into conformity therewith, and means for circulating lubricant through the support to cool the bearings and associated parts against heat conduction.

50 23. A rolling mill comprising a rotating die, an electric motor connected by a suitable coupling for driving said die, milling rollers for reducing a metallic blank to the required thickness by expanding its diameter and face, and means for feeding successive blanks through the mill.

In testimony whereof, I have hereunto signed my name at Philadelphia, Pennsylvania, this 12th day of May, 1924.

60 JOHN W. SMITH.
